FASTENING INSERTING MACHINE

Michael F. Brogan, deceased, late of Lawrence, Mass., by Theresa M. Brogan, administratrix, Lawrence, Mass., assignor to United Shoe Machinery Corporation, Paterson, N. J., a corporation of New Jersey

Application October 26, 1932, Serial No. 639,582

12 Claims. (Cl. 1—20)

This invention relates to machines for use in the manufacture of shoes and is illustrated herein as embodied in a machine particularly adapted to secure an upper in lasted relation to an insole upon a last by staples driven through the upper and through a rib or other projection on the insole.

It is desirable, in order to obtain a properly lasted shoe, that the rib or projection on the insole should not become distorted or displaced toward the edge of the shoe under the lasted tension of the upper. This sometimes happens when the insole is formed of flexible stock and the rib or projection on the insole is not reinforced.

An object of this invention is to provide a fastening inserting machine arranged to overcome the above-mentioned difficulties. In accordance with this object a feature of this invention consists in a fastening inserting machine provided with knives having cutting surfaces arranged to cut the ends of a length of fastening material obliquely, means for forming a fastening from the length of fastening material, a driver for inserting the fastening into a projection on a work piece and an anvil arranged to engage the projection and having clenching surfaces arranged to deflect the ends of the fastening in curved paths located in substantially parallel planes. As illustrated, the machine is provided with two pairs of knives having oppositely inclined cutting surfaces arranged to cut wire to form a length of wire having oblique ends, and staple forming mechanism for forming the wire into a staple with the oblique ends located in substantially the same plane. The machine is provided with a driver for inserting the staple into a shoe and with an anvil arranged to deflect the ends of the staple as they penetrate the shoe upwardly and back into the shoe in such a manner that the ends of the staple follow curved paths located in planes substantially normal to the cross bar of the staple to clamp the staple in the shoe. The turning of the ends of the staple legs upwardly and back into the rib or projection of the insole tends to reinforce and strengthen the insole rib or lip in such a manner that displacement or distortion of the rib or lip under the tension of the lasted upper and consequent loosening of the upper are substantially reduced.

The novel features of the invention will now be more particularly described by reference to the accompanying drawings and thereafter pointed out in the claims.

In the drawings,

Fig. 1 is a view in side elevation illustrating a

portion of the machine embodying one form of the present invention;

Fig. 2 is a view partly in section along the line II—II of Fig. 1;

Fig. 3 is an exploded view of mechanism for severing the fastening material;

Fig. 4 is a front view of the staple formed in accordance with the present invention;

Fig. 5 is a side view of the staple;

Fig. 6 is a sectional view of a work piece taken through a staple showing the direction of clench; and

Fig. 7 is a view partly in section showing the position of the lasting and fastening inserting instrumentalities after a staple has been inserted in the work.

The present invention is illustrated as embodied in a machine of the type disclosed in United States Letters Patent No. 1,796,451, granted March 17, 1931 upon an application filed in the name of George Goddu. The invention, however, is not limited in its utility to application in machines of this type but may be embodied in other types of machines. The parts of the machine common to both the machine disclosed in said Letters Patent and to the illustrated machine are not described herein except in so far as is necessary for a complete understanding of the present invention. Reference may be had to the above-mentioned Letters Patent for a complete disclosure of the parts of the machine not described in detail in this application.

The machine disclosed in said Letters Patent is provided with a head mounted on a column within which is mounted the power shaft of the machine. The power shaft is connected by bevel gears to a horizontal shaft upon which are mounted the cams for operating the lasting pincers 30 and for operating the staple forming and driving instrumentalities. The cams for operating the pincers 30 may, at the will of the operator, be held stationary during operative movement of the cam shaft to permit the machine to be used solely as a stapling machine without pulling the upper.

The present machine is provided with an anvil 32 which is adapted to engage the inside of a rib of an insole to position the shoe properly relatively to the fastening inserting means and to the lasting pincers 30. The anvil 32 is also provided with clenching cavities which turn the legs of the staple upwardly as shown in Figs. 6 and 7. The anvil 32 is mounted at the front of the machine and may be yieldably mounted if

- so desired. The pincers or grippers 30 are operated to pull the upper heightwise of the last and then inwardly over the margin or feather of the insole as described in the above-mentioned Letters Patent. An overlaying member 34 comprising a staple guiding nozzle is moved in a direction inclined to the bottom face of the sole to lay the margin of the sole over the feather of the insole and against the rib to hold the upper while the staple is being driven by a driver 36 to fasten the upper to the rib, the legs of the staple penetrating entirely through the work and being deflected upwardly and back into the rib to clinch the staple.
- 15 In order to provide ample room for the manipulation of the shoe and for the operation of the pincers or grippers 30, the staple forming mechanism (which will hereinafter be described in detail) is so constructed and arranged as to form 20 a staple in a location out of alignment with the staple driver 36 and above the path of movement of the driver. The machine is provided with means for transferring the staple downwardly into alignment with the driver between 25 successive staple forming and driving operations. For forming the staple there is provided an inside former 38 supported on a stationary bracket 40 secured to the head of the machine by a cap screw 42. The remainder of the staple forming 30 mechanism and the means for transferring the staple from forming position to driving position with the exception of the wire cutting means are carried by a slide 44 which also carries the staple guiding nozzle 34, this slide being mounted 35 for reciprocating movement in an inclined guideway in the head of the machine. The slide is moved along its guideway through connections to a cam which is clearly described in the Letters Patent above referred to.
- 40 Attached to a stationary bracket 39 secured to the head of the machine in adjustable relation to the inside former 38 is a wire guiding tube 46, to which wire is fed by a pair of feed rollers (not shown). The wire is advanced a predetermined 45 distance by said feed rollers. The wire is fed forwardly over a guide member 48 which is secured to the forward end of the movable slide 44 by a stud 49. The guide member 48 is provided with a pair of substantially U-shaped members 50, 52 which are clamped to the top of the 50 guide member 48. The top of the guide member 48 and the lower portions of the U-shaped members 50, 52 form a slot or recess through which the wire passes and which positions the 55 wire in proper relation to wire cutting means. The nozzle 34 is secured in position on the member 48 by means of a set screw 54 which holds the nozzle 34 against movement relatively to the member 48. The upper end of the member 48 is shaped to prevent interference with the stationary parts of the staple cutting and forming mechanism.
- 60 Mounted on a block 55 secured to the stationary bracket 39 by a stud 57 in front of the wire guiding tube 46 is a wire cutting knife 56 which is provided with an inclined cutting edge 58. Co-operating with the knife 56 is a movable cutting knife 60, secured to a block 47 attached to the slide 44 by a stud 49 which operates to sever a 65 length of wire, the cut being formed at a substantial angle or obliquely to the longitudinal axis of the wire. The other end of the severed length of wire is cut by a pair of knives 62, 64 at an angle inclined in a direction opposite to 70 the angle at which the first end of the length is

cut. The member 62 is attached to the stationary bracket 39 by a stud 41 and is provided with a cutting edge 66 inclined in a direction opposite to the inclination of the cutting edge 58 on the knife 56. The member 64, which co-operates with the knife 62, is mounted on the slide 44 and is movable with the cutting member 60. The length of wire is cut with the beveled ends inclined downwardly and toward each other.

The knives 60, 64, above referred to, are mounted on an upward extension of the nozzle 34 rearwardly of the member 48 and prior to the wire severing operation are located just rearwardly of the stationary knives 56, 62. The inner surfaces of the members 60, 64 are provided with a pair of members or outside formers 68 which co-operate with the inside former 38 to form the length of wire into a staple. The members 68 are spaced apart a distance sufficient to clear the inside former 38. After the staple has been formed, it is in a position to be transferred to the driver passage 70 in the nozzle 34. The staple 72 after it has been formed is moved downwardly into the driver passage 70 in the nozzle 34 by downward movement of the outside former 68 in the manner described in Letters Patent No. 1,796,451 above referred to.

At the same time that the staple 72 is being formed the nozzle 34, also secured to the slide 44, is being moved toward the shoe. The upper U of the shoe in the meantime has been gripped by the pincers 30. The lasting pincers are then given an upward movement to tension the upper and when the lasting pincers 30 have moved inwardly to lay the upper over an insole S the nozzle 34 engages the upper to lay the upper over the margin of the insole. During these operations, the anvil 32 which also acts as a shoe rest, engages the inner edge of the rib R thereby resisting the pull of the pincers 30 and acting as a gage or guide for the work. The operation of the lasting pincers 30 and the staple inserting instrumentalities described just above is substantially the same as in the Letters Patent above-mentioned to which reference may be had for a more complete description of the construction and operation of these parts.

The legs of the staple 72 are provided with ends 73 beveled in substantially the same plane. When the staple 72 is transferred to the driver passage 70 in the nozzle 34 the staple is in a substantially horizontal position with the beveled portion of the staple legs lowermost. When the staple 72 is driven into the work, the staple because of the beveled ends tends to follow an upwardly curved path in the work. The bevel, however, is sufficiently great to prevent the staple from curling in the work but when the end of the staple strikes the anvil 32 the legs are turned upwardly and back into the work to secure the staple in the work. By turning the staple upwardly in this manner the rib R is made more rigid and consequently will not be distorted or displaced as readily as when the legs of the staple are clenched in some other manner.

Having thus described the invention, what is claimed as new and desired to be secured by Letters Patent of the United States is:

1. A machine for inserting fastenings having, in combination, knives having oppositely inclined cutting surfaces arranged simultaneously to cut both ends of a length of fastening material at opposite angles to the longitudinal axis of the fastening material, means for forming a fastening from said length of fastening material with

the angularly cut ends in substantially the same plane, means for inserting the fastening into a projection on a work piece, and an anvil arranged to engage said projection and having clenching surfaces arranged to deflect the ends of the fastening in curved paths located in substantially parallel planes.

2. A machine for inserting fastenings having, in combination, means having oppositely inclined cutting surfaces arranged simultaneously to cut both ends of a length of fastening material to form oblique oppositely inclined ends, means for forming a staple from said length of fastening material with the oblique ends of the staple located in substantially the same plane, a driver for inserting the staple through a projection on a work piece, and an anvil arranged to engage said projection and having clenching surfaces arranged to cause the ends of the staple to follow curved paths located in planes substantially normal to the cross bar of the staple.

3. A machine for inserting fastenings having, in combination, two pairs of cutting members having oppositely inclined cutting edges arranged simultaneously to cut both ends of a wire to form a length of wire having oppositely inclined oblique ends, means for forming said wire into a staple with the oblique ends located in substantially the same plane, means for inserting said staple through a shoe upper and through a rib on an insole, and an anvil formed and arranged to engage the rib and to cause the oblique ends of the staple to follow curved paths located in planes substantially normal to the cross bar of the staple to clinch the staple in the rib.

4. A machine for inserting fastenings having, in combination, two pairs of cutting elements having oppositely inclined cutting surfaces arranged to cut the ends of a length of fastening material at an angle oblique to the longitudinal axis of the fastening material, means for forming a staple from said length of fastening material with the obliquely cut ends located in substantially the same plane, means for driving the staple through a projection on a work piece, and an anvil arranged to engage said projection and to engage the staple to deflect the legs in curved paths back into the projection.

5. A machine for inserting fastenings having, in combination, two pairs of cutting members having oppositely inclined cutting edges arranged to cut wire to form a length of wire having oblique ends, staple forming mechanism for forming the severed length of wire into a staple with the oblique ends located in substantially the same plane, a driver for inserting the staple into a rib on a shoe sole, and an anvil arranged to engage the rib and to deflect the ends of the staple as they penetrate the rib upwardly and back into the rib to clinch the staple in the rib.

6. A machine for inserting fastenings having, in combination, two pairs of knives having oppositely inclined cutting edges arranged to cut wire to form a length of wire having oppositely inclined ends, staple forming mechanism for forming the cut length of wire into a staple with the oblique ends located in substantially the same plane, a driver for inserting the staple through an upper and through a rib on an insole, and an anvil arranged to engage the inner side of the rib to deflect the ends of the staple as they penetrate the rib upwardly in curved paths.

7. A machine for inserting fastenings having, in combination, two pairs of knives having oppo-

sitely inclined cutting surfaces arranged to cut ends of a length of wire at opposite angles to the longitudinal axis of the wire, inside and outside formers for forming a staple from the length of wire with the angularly cut ends in substantially the same plane, a driver for inserting a staple through a shoe upper and through a rib on an insole, and an anvil arranged to engage the rib and having clenching surfaces arranged to deflect the ends of the fastening back into the rib in curved paths located in substantially parallel planes.

8. A machine for inserting fastenings having, in combination, knives having oppositely inclined cutting surfaces arranged to cut a length of wire with oblique oppositely inclined ends, inside and outside formers for forming the length of wire into a staple with the cut ends of the staple in substantially the same plane, a driver for inserting the staple through an upper and through a rib on an insole, and an anvil arranged to engage the inner side of the rib to deflect the ends of the staple as they penetrate the rib upwardly in curved paths located in substantially parallel planes.

9. A machine for inserting fastenings having, in combination, knives having oppositely inclined cutting surfaces arranged to cut the ends of the fastening material obliquely, inside and outside formers for forming said length of fastening material into a staple, a driver for inserting the staple through the marginal portion of an upper and through a rib on an insole, and an anvil arranged to engage the inner side of the rib and to deflect the ends of the staple as they penetrate the work upwardly and away from the body of the insole in curved paths located in planes substantially normal to the cross bar of the staple to clinch the staple in the rib.

10. A machine for inserting fastenings having, in combination, two pairs of knives having oppositely inclined cutting surfaces arranged simultaneously to cut both ends of a length of wire, staple forming mechanism for forming a severed length of wire into a staple with the inclined ends of the staple located in substantially the same plane, a driver for inserting the staple into the marginal portion of an upper and through a rib on an insole, and an anvil having clenching surfaces arranged to engage the ends of the staple as they penetrate the rib to cause the ends of the staple to follow curved paths located in planes substantially normal to the cross bar of the staple.

11. A machine for inserting fastenings having, in combination, two pairs of co-operating cutters, the cutting edges of each pair being oppositely inclined and arranged to cut wire from a length of wire having oblique ends, staple forming mechanism for forming the wire into a staple with the oblique ends located in substantially the same plane, a driver for inserting the staple through an upper and through a rib of an insole, and an anvil arranged to engage and support the rib during the driving operation and to deflect the ends of the staple, as it penetrates the upper and the rib, upwardly and into the rib in planes substantially normal to the cross bar of the staple to clinch the staple in the rib.

12. A machine for inserting fastenings having, in combination, two pairs of cutting members having oppositely inclined cutting edges arranged to cut wire to form a length of wire having the ends thereof severed at opposite angles to the longitudinal axis of the wire, an inside former, outside formers movable relatively to the inside former form forming the wire into a staple with

the oblique ends located in substantially the same plane, a driver for inserting the staple through an upper and through the rib of an insole, and an anvil engaging the rib on the insole to support the 5 rib during the fastening inserting operation and to deflect the ends of the staple, as it penetrates

the upper and the rib on the insole, upwardly and back into the rib to stiffen the rib and to clinch the staple in the rib.
